UNITED STATES PATENT OFFICE.

JOHN WARNCKE, OF BUFFALO, NEW YORK.

IMPROVED COMPOSITION FOR RESTORING COLORS TO CLOTH, &c.

Specification forming part of Letters Patent No. **37,838**, dated March 3, 1863.

To all whom it may concern:

Be it known that I, JOHN WARNCKE, of the city of Buffalo and State of New York, have discovered a new composition of matter for restoring colors to faded and soiled cloth, which may be applied to plush, velvet, or other cloth used for covering railroad-car seats, and to carpets and the like, without removing the cloth from the seats or the carpets from the floor, and which is also applicable to all kinds of garments, silk, cotton, and woolen goods; and I do hereby declare that the following is a full and exact description of the said composition and the manner of applying or using the same, to wit:

The ingredients used are as follows, and substantially in the following proportion: Two gallons rain-water, two ounces ammonia, two and one-half ounces cochineal, one ounce cudbear, one-half ounce English tin, one-fourth ounce spirit of salt, one-fourth pint alcohol, thoroughly mixed, which forms a fine liquid compound.

This composition is applied warm with a stiff brush. In applying it to plush, velvet, or other covering of car-seats, or to carpets, the dust should be whipped or brushed out of the cloth, as may be convenient, without removing the cloth from its place. The composition is then

applied with a stiff brush quickly passed over the cloth, thoroughly saturating the cloth with the compound, the brush also raising the nap on the cloth. This adds to and quickly brings out the colors as bright and as permanent as when the cloth was new.

This is a great saving of labor and expense, as it may be applied without first washing or cleansing the cloth and without removing it from its place. When the cloth is dry it should be thoroughly brushed with a dry brush.

By using this composition as described the cloth may be kept bright and in a usable condition for a much greater length of time than if not used. Hence there is great economy in its application to soiled or faded clothes generally, and is particularly useful for restoring and preserving the colors on the cloth of car-seats, chair-seats, and carpets, &c.

I claim—

The composition of matter herein described and the mode of applying it for restoring colors to faded and soiled cloth, substantially as herein set forth.

JOHN WARNCKE.
